Fig. 3

FIG. 1 is a front elevational view of a disc brake friction pad assembly showing my new design;

FIG. 2 is a rear elevational view thereof;

FIG. 3 is a top plan view thereof; and

FIG. 4 is a side elevational view thereof.

The characteristic feature of my design resides in a layer of friction material on the rear face of the backing plate superposed over and co-extensive with the friction material on the front face of the backing plate.

I claim:

The ornamental design for a disc brake friction pad assembly, substantially as shown and described.
